UNITED STATES PATENT OFFICE.

CHARLES E. HUNT, HENRY L. FERRIS, AND NATHAN B. HELM, OF HARVARD,
ILLINOIS.

HAY-CARRIER.

SPECIFICATION forming part of Letters Patent No. 307,950, dated November 11, 1884.

Application filed September 22, 1884. (No model.)

To all whom it may concern:

Be it known that we, CHAS. E. HUNT, HENRY L. FERRIS, and NATHAN B. HELM, citizens of the United States, residing at Harvard, in the county of McHenry and State of Illinois, have invented certain new and useful Improvements in Hay-Carriers; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a vertical sectional view of our device. Fig. 2 is a plan view of the ring, and Fig. 3 is a transverse vertical sectional view of the device.

The invention relates to reversible carriers 20 for hay or other material; and its object is to provide a locking device to sustain the load of the carrier at any desired point, usually over the loaded wagon.

The invention consists in constructing a device 25 by which the actuating-rope of the carrier may be reversed, the said device swiveling upon the lower end of the carrier.

It consists, further, in attaching within the carrier a locking device of peculiar construction, hereinafter described, which is tripped or opened by a stud or projection fixed to the beam upon which the carrier travels.

In the accompanying drawings, A represents the beam or way, upon which the carrier travels in the usual well-known manner.

B is the carrier, of the usual shape, having four upwardly-extending arms, b b, each provided with its wheel b', to travel upon the beam A. Surrounding the carrier near its lower end 30 is the circumferential groove b², below which is the outwardly-inclined circular flange b³.

b⁴ is an opening ascending into the carrier from a point centrally within the flange b³, the function of which opening is hereinafter explained. The carrier is in practice cast into two similar lateral parts or halves.

C is a swivel-ring fitting and turning in the groove b². The said ring has on one side an extension, c, in which a pulley, c', has bearings, and on the opposite side an extension, c², provided with a proper opening, in which

the lifting and carrying rope is knotted or otherwise secured.

D is the hanging pulley that supports the load, inclosed and pivoted in the block d. The 55 lower end of the block d has pivoted to it the usual hook, d', and has rising vertically from its end the rod or extension d², provided with the hemispherical head d³, as shown.

d⁴ is a retaining-loop, pivoted to the block, 60 by which the rope d⁵ is kept upon the pulley D. The said rope runs from the extension c² below the pulley D, and thence over the pulley c' down to the hand of the person operating the machine. The swiveled ring C is made in two 65 similar lateral halves bolted together, the pulley c' having one bearing in each half.

E is a locking-block pivoted in the central vertical line between the two sides of the carrier vertically above one edge of the opening b⁴. 70 The block E has on its upper edge the rectangular notch e, the bottom of which is flush with the upper edge of the carrier when the block is horizontal.

e' e² are the extensions forming the notch on 75 each of its sides, and e³ is a semicircular slot in the block E, below and concentric with its pivot.

e⁴ is a vertical slot opening upward centrally into the slot e³.

80 F is a retaining-piece pivoted by one of its upper corners between the sides of the carrier over the edge of the opening b⁴, diametrically opposite to the pivot-point of the locking-block. The opposite upper corner of the retaining piece or block has crossing from one of its side plates to the other a transverse rod, f, which passes through the slot e³, and when the device is unlocked drops into the slot e⁴.

f' is the concaved lower edge of the retaining-block F, against which the rounded head of the extension d² strikes when the pulley D is drawn up, thereby making the hook f' 90 on the retaining-block catch below the edge of said head.

G is a tripping-block of rectangular shape, bolted to the under surface of the beam A in such position that it will trip the locking-block when the carrier is over the wagon-load of hay.

H is a slotted directing-pin, through the longitudinal slot of which a pivot runs, having its ends fixed in a central perpendicular slot

in the locking-block. The said pin drops in front of the rod *f* and directs it into the slot *e*² out of the slot *e*¹.

The operation of the device is as follows: Supposing the rounded head *d*² is locked or retained by means of the concaved edge and hook of the retaining-block, the locking-block being set at an angle, with one of its arms or extensions elevated above the other, the notch *e*¹ out of the horizontal, and the rod *f* lying in the slot *e*². The carrier is moving from the mow toward the loaded wagon. When over the latter, the tripping-block *G* passes into the notch *e*¹ and strikes the elevated arm on the side of the same, partially rotating the locking-block. The rod *f* drops into the slot *e*², and the retaining-block turns on its pivot, releasing the head *d*² and unlocking the pulley *D* and attached fork, so that the latter can be lowered and loaded. When the carrier is again drawn toward the mow, after the pulley *D* and fork have been raised, the locking-block is moved into locking position as it passes from under the tripping-block. The pin *H* prevents the rod *f* from passing the slot *e*².

Having thus described our invention, what we desire to secure by Letters Patent is—

1. In a hay-carrier, the combination of the locking-block *E*, tripping-block *G*, retaining-piece *F*, and slotted directing-pin *H*, substantially as specified.

2. The combination of the beam *A*, having attached one or more tripping-blocks, *G'*, with the carrier *B*, moving thereon, and provided with the swiveled ring *C*, and the locking device composed of the locking-block *E*, the retaining-piece *F*, the directing-pin *H*, and the rounded head *d*², made on the sheave of the hanging pulley *D*, substantially as specified.

In testimony whereof we affix our signatures in presence of two witnesses.

CHARLES E. HUNT.

HENRY L. FERRIS.

NATHAN B. HELM.
